ALPHABETICAL PRINTING MECHANISM

Filed June 26, 1929.

INVENTOR

William W. Lasker

BY Barton A. Bean, Jr.
ATTORNEY

UNITED STATES PATENT OFFICE

WILLIAM W. LASKER, OF BROOKLYN, NEW YORK, ASSIGNOR TO REMINGTON RAND
INCORPORATED, OF NEW YORK, N. Y., A CORPORATION OF DELAWARE

ALPHABETICAL PRINTING MECHANISM

Application filed June 26, 1929. Serial No. 373,852.

This invention relates to alphabetical printing mechanisms of the type shown in Letters Patent of the United States to Lasker #1,692,215, November 20, 1928.

5 The principal object of this invention is the provision of an improved pin basket construction in which the parts are readily assembled, and sure of operation.

10 The invention relates specifically to improvements in means for positively locking the home position stop in operative position and positive means for withdrawing said locking means upon a setting operation of the stop pins.

15 The improvements comprise other features of construction which will appear from the following description taken in connection with the drawing.

The figure of the drawing is a cross section 20 through a pin basket with one side plate removed, showing one column of stop pins, a stop sector and a type sector in side elevation.

25 In this general type of machine, the adding and printing head comprises a plurality of units some of which add and print numbers and others of which print letters of the alphabet.

The alphabetical unit comprises a pin basket 10, a cooperating stop sector 11 and a type sector 12.

30 The pin basket 10 includes any desired number of rows of stop pins generally indicated at 13. Each row of stop pins comprises twelve pins arranged in the order indicated 35 on the drawings. The sector 11 carries a heel 14 cooperating directly with the stop pins in position eleven, and zero to eight.

The twelve or home position of the sector is 40 controlled by a stop lug 15 on a member 16 pivotally and slidably supported on a rod mounted in the side plates 17 which together with an upper stop pin guide plate 18 and a lower stop pin guide plate 19 constitute the 45 frame of the pin basket. Only one of the side plates 17 is shown.

The stop lug 15 is held in its operative position by a slide 20 drawn to the left by a spring 21 anchored to a cross plate 22 supported in the side plates 17 and provided at

its upper edge with teeth constituting guides for the members 16. The slides 20 are supported at their right-hand ends by a rod 23 mounted in the side plates 17 and at their other ends are provided with downwardly 55 extending portions 24 slideable on the upper stop pin guide plate 18. The movement of the slides 20 toward the left is limited by a plate 25 supported in the side plates 17 and provided with an upwardly extending flange 60 notched at 26 to provide guides for the members 16. The members 16 are urged counterclockwise by springs 27 suitably anchored to said members and spring hooks secured to the cross plate 22.

65 The lower edge of the slide 20 is provided with a series of cams 30 one for each of the stop pins except the twelve pin. The stop pins carry laterally extending pins 31 shaped as shown for cooperation with the 70 cams 30 on the slides 20. The nine pin does not extend into the path of the heel 14 of the stop sector 11. A common nine stop 32 supported in the side plates is provided to arrest the stop sectors in the nine position when 75 the nine stop pin is set.

When any one of the stop pins eleven and zero to nine is raised by mechanisms not shown here but well known in the art, the slide 20 is cammed to the right to free the 80 member 16 which however will be held in the position shown by the spring 27.

85 The setting or raising of the stop pin twelve will have no effect on the member 16. The upper end of this pin is extended into cooperative relation with a lever hook 33 pivoted on the stop sector 11 and normally in engagement with a lug 34 on the type sector 12 extending through a long slot 35 in the stop sector 11. This engagement is maintained by a lever 36 mounted on the stop sector 11 and spring pressed by a tension spring 37 connected to the type sector 12.

90 When the twelve pin is raised it will cam the hook lever 33 out of engagement with the lug 34 and permit the type sector 12 to move forward twelve steps with respect to the stop sector 11 during a subsequent part 95 of the operation of the machine.

The sectors 11 and 12 are normally held in 100

their home position by a bail 38. The type sector 12 is urged counter-clockwise to position the type at the printing line by a spring 39 suitably anchored to a fixed part of the machine. The stop sector 11 is carried with the type sector by the lug 34 and lever hook 33. When the lever hook 33 is released, the type sector 12 is controlled to be projected forward by the springs 37 and 39 to an extent of twelve steps.

10 The stop sector 11 is released when any one of the stop pins eleven and zero to nine is set. The type sector 12 is released for twelve steps of forward movement with respect to the stop sector 11 when the twelve stop pin is set.

15 After the stop pins have been set, the main shaft 40 is rocked forward clockwise by a means well known which movement 20 through a link 41 rocks the bail 38 counter-clockwise. If one of the pins eleven and zero to nine has been set, the spring 39 will move the stop sector 11 and type sector 12 counter-clockwise, and the slide 16 which is 25 now free to pivot will be cammed clockwise. This movement of the sectors will continue until the heel 14 of the stop sector 11 will be arrested by a stop pin or the common nine stop. The impression will then be made and 30 the parts restored in the usual manner. This is the operation when letters A—L are positioned for printing.

35 When the twelve stop pin is set singly, the member 16 will be held locked and the stop sector 11 will be held in home position. This pin releases the type sector 12 from the stop sector 11 and permits it to move forward twelve steps to present the first letter M of the second group M—Z at the printing line. 40 When the twelve pin is set in combination with any other pin, the stop sector 11 will be arrested by the stop pins eleven and zero to eight or the common nine stop as usual and the type sector 12 will be permitted to move 45 forward twelve steps with respect to the stop sector 11, to present letters N to Z to the printing line.

50 The important feature of this invention is in the provision of a home position stop sector control which is positively locked in operative position and whose movements are in the plane of the stop sector. The slot in the slide 16 is provided for safety purposes which permits the slide to be pushed to the left by 55 the heel 14 in case the slide 20 has been moved under the slide 16 by premature restoration of a stop pin.

55 What I claim as new and desire to secure by Letters Patent, is:

60 1. In mechanism of the character described, the combination of rows of stop pins, a home position stop for each row of stop pins, sectors controlled by said pins and stops, slides operatively mounted between adjacent rows 65 of stop pins and normally locking said stops,

and means for moving each slide by a setting movement of any one of the corresponding stop pins and thereby permitting withdrawal of said home position stop.

2. In mechanism of the character described, 70 the combination of rows of stop pins, a home position stop for each row of stop pins, sectors controlled by said pins and stops, slides operatively mounted between adjacent rows of stop pins and normally locking said stops, 75 cams on said slides corresponding in number with said stop pins, and means on said stop pins cooperating with said slides to move said slides out of locking relation with said stops.

3. In mechanism of the character described, 80 the combination of rows of stop pins, a home position stop for each row of stop pins, slides mounted between adjacent rows of stop pins normally engaging and holding said home position stops in operative position, and 85 means for withdrawing said slides from effective position by movement of any corresponding stop pin.

4. In mechanism of the character described, 90 the combination of slidable stop pins, a pivoted home position stop, means normally preventing movement of said stop, and cooperating means between said stop pins and said first mentioned means for withdrawing said preventing means by movement of said 95 stop pins.

5. In mechanism of the character described, 100 the combination of stop pins, a depressible home position stop, a sector controlled by said stop pins and stop, means for normally locking said stop in operative position, a connection between said stop pins and said means for withdrawing said means by a setting movement of said stop pins, and a heel on 105 said sector cooperating with said stop and stop pins, said heel and stop having cooperating surfaces functioning to depress said stop upon advancing movement of said sector.

Signed at Brooklyn in the county of Kings and State of New York this 21 day of June, 110 A. D. 1929.

WILLIAM W. LASKER.
